WINDOW VENTILATOR

William B. Nye, Lakewood, Ohio, assignor of one-half to James Faus, North Olmstead, Ohio

Application July 4, 1945, Serial No. 603,143

5 Claims. (Cl. 98—99.8)

1

This invention relates broadly to window ventilators and more specifically to improvements in ventilators of the type which are adapted to effect the limited passage of air therethrough, the deflection of the air currents entering the ventilator, the diversion of rain, and the preclusion of insects and heavy particles of air-borne dust.

One of the objects of the invention is to provide a ventilator unit of rectangular cross section having rigid end portions and an intermediate wire mesh or screen portion adapted to effect the circulation of air therethrough in a tortuous path.

Another object of the invention is to provide a ventilator unit having a deflector therein to control the currents of air passing therethrough and preclude the entry of rain.

Another object of the invention is to provide a ventilator comprising a plurality of like units adapted for assembly with each other in superposed relation.

Another object of the invention is to provide a baffle formed from a finely-woven screen section or multiple layers of screen disposed to control the passage of air therethrough.

Another object of the invention is to provide a ventilator unit having a diagonal plate extended through the length thereof to serve as an air or rain deflector and to increase the rigidity of the screen structure.

Another object of the invention is to provide rigid sheet metal end sections for the ventilator units having telescopic sleeves thereon which are formed with inclined end walls to facilitate the ready insertion or removal of the units.

Another object is to construct a ventilator comprising an assembly of similar units having interengaging members therein disposed to facilitate the alignment of the units when arranged in superposed relation.

Other objects and advantages more or less ancillary to the foregoing and the manner in which all the various objects are realized will appear in the following description, which considered in connection with the accompanying drawings, sets forth the preferred embodiment of the invention.

Referring to the drawings:

Fig. 1 is an elevational view of a window illustrating a pair of the improved ventilator units in place therein;

Fig. 2 is a transverse section through the window and ventilator illustrated in Fig. 1, the section being taken on the line 2—2 of Fig. 1;

Fig. 3 is a front elevational view of one of the improved ventilator units;

2

Fig. 4 is a vertical section through an end portion and sleeve of the ventilator unit illustrated in Fig. 3, the section being taken on the line 4—4 of Fig. 3;

5 Fig. 5 is a vertical section through the ventilator unit adjacent the end portion thereof, the section being taken on the line 5—5 of Fig. 3;

10 Fig. 6 is a transverse section through a ventilator unit of a modified form, the section being taken through the central portion thereof; and

Fig. 7 is another modified form of a ventilator unit illustrating an alternate type of baffle, the baffle illustrated herein being formed of a section of fine mesh screen.

15 Referring first to Figs. 1 and 2, the ventilator comprises a plurality of rectangular screen units 10 preferably formed of a width substantially equal to the thickness of the window sash 11 and of suitable length for assembly in window openings of standard width. The major portion of the ventilator units are formed of screen, such for example as the mesh normally used in the construction of fly screens. The screen is folded in tubular form of rectangular cross section and provided with sheet metal end members or thimbles 12 soldered, welded, or otherwise affixed to the screen. The end members 12 are provided with telescopic sleeves 13 formed with mitered parallel outer ends 14 to facilitate the removal of the units by elevating one end thereof to a point which will accommodate the retraction of the ventilator unit over the stops 15 in the window frame. The angle of the mitered ends of the sleeves 13 is designed for overlapped relation with stops 15 in the average installation. The telescopic sleeves 13 further provide for the installation of the ventilator units in windows of various widths. The body M of the screen is preferably formed with a strip 17 of sheet metal or substantially imperforate material disposed in diagonal relation therein. Air passes through this form of ventilator by entry through a subjacent unit, through the bottom face 19 of the unit, and thence through the inner vertical wall 20 thereof.

Referring next to Figs. 2, 3 and 5, legs 21 are secured to the lower faces of the thimbles 12 adjacent the screen section M. The legs are disposed outwardly from the vertical center line of the units to facilitate the level mounting thereof on the inclined surface of the bottom member 22 of the window casing. The upper faces of the sleeves are provided with holes 23 for the reception of the legs 21 depending from the super-

jacent unit of the ventilator as assembled in a window frame.

In the modified baffle structure illustrated in Fig. 6, the upper wall of the screen is bent downwardly and inwardly to form a longitudinal V-section 24 which obviously will multiply the number of strands across the upper area of the unit and thus retard the circulation of air through the unit and arrest the passage of rain through that portion of the ventilator. This embodiment is primarily adapted for use as a base section of the assembly where the window sill 18 obstructs the lower portion thereof, and may be used in combination with the preferred structure illustrated in Fig. 5.

In the modification illustrated in Fig. 7, the intermediate screen section and the diagonal baffle therein are folded from one piece of mesh, the baffle portion 25 thereof being formed of a finely woven pattern capable of precluding the passage of rain or from a plurality of layers of screen disposed with the strands of the various layers in staggered relation to effectively reduce the interstitial area.

Among the many advantages attending the improved ventilator are economy of manufacture, due to the simple construction and the use of cheap, easily procurable materials; efficiency of operation, chiefly due to the use of the total height for ventilation and the well designed and proven baffle means; ease of insertion and removal resulting from the use of the mitered ends of the sleeves; and sales appeal resulting from the features mentioned above combined with natural attractiveness and the ability to add sections to give increased ventilation area.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. As an article of manufacture, a window ventilator of the type adapted to be inserted below a window sash comprising a wire mesh tube of rectangular cross-section, sheet metal thimbles secured thereto, sheet metal sleeves telescopically engaged with said thimbles, and a baffle in said tube for the deflection of the air passing therethrough.

2. As an article of manufacture, a portable win-

dow ventilator comprising a rectangular tube formed of fly screen, baffle means therein, imperforate end portions on said tube, sheet metal sleeves on said end portions, the outer ends of said sleeves being in oblique relation to the axis of said tube and in parallel relation with each other to facilitate the elevation of one end of the ventilator when mounted in a window.

3. As an article of manufacture, a window ventilator of the type adapted to be inserted below a window sash comprising a wire mesh tube of rectangular cross-section, sheet metal thimbles secured thereto, sheet metal sleeves telescopically engaged with said thimbles, a longitudinal stiffening member in said tube constituting a baffle.

4. A window ventilator comprising a plurality of similar rectangular screen units adapted for assembly in superposed relation with each other, said units embodying top, bottom and side walls, slide sleeves on the end portions thereof for engagement with the side frames of a window and deflectors in said units for directing the egress of air through the top portions of each of the respective units.

5. A window ventilator comprising a plurality of similar rectangular screen units adapted for assembly in superposed relation with each other, said units embodying top, bottom and side walls, slide sleeves on the end portions thereof for engagement with the side frames of a window, baffles in said units for deflecting upwardly the currents of air passing through the ventilator, and interengaging members in the units disposed to facilitate the proper assembly of the units within a window frame.
